UNITED STATES PATENT OFFICE.

FREDERICK MAX PORITZ, OF NEW YORK, N. Y., ASSIGNOR TO STAR CHANDELIER CO. INC., OF NEW YORK, N. Y., A CORPORATION OF NEW YORK.

DESIGN FOR A CHANDELIER.

Application filed August 23, 1922. Serial No. 3,529. Term of patent 3½ years.

To all whom it may concern:

Be it known that I, FREDERICK MAX PORITZ, a citizen of Germany, residing in New York, county of New York, and State of New York, have invented a new original, and ornamental Design, for a Chandelier, of which the following is a specification, reference being had to the accompanying drawing, forming part thereof.

The figure is a perspective view of a chandelier, showing my new design.

I claim:—

The ornamental design for a chandelier, as shown.

FREDERICK MAX PORITZ.

Witnesses:

ELIAS BASILA,
JANET MATLIN.
